UNITED STATES PATENT OFFICE.

PAUL T. ZIZINIA, OF BELMAR, NEW JERSEY.

BEACH-PROTECTING AND BEACH-BUILDING STRUCTURE.

Application filed August 14, 1926. Serial No. 129,124.

The present invention relates to a structure especially suitable for use along ocean water fronts, and has to do particularly with the protection of the beach from the action of 5 storms and currents and with the actual building up of desirable sand beach.

Much difficulty in the way of destruction of sand beaches by heavy seas and currents is experienced along ocean front property. A

10 particular source of this difficulty is the presence of definite ocean currents moving adjacent the shore and persisting in the same general direction throughout all or a greater part of the year. Such currents move along

15 the shore line carrying great quantities of sand, and the tendency is to remove sand from certain parts of the shore line and deposit it at other points. This results in a shifting of the shore line and an altering of the character

20 of the beaches. At certain places erosion of the beaches occurs to such an extent as to cause great property damage. Such a situation exists, for instance, along particularly the northern portion of the New Jersey seacoast.

25 A definite movement of the water to the north along this coast persists throughout the greater part of the year, and certain sections of the shore line suffer acutely from the destructive effect of the ocean current.

30 The most successful means which have been proposed to preserve the beaches against the action of the waves and the ocean currents are the heavy stone breakwater and the low wood beach groin. The stone breakwater is

35 a massive continuous structure extending out from the shore a considerable distance into the water and reaching to a height of several feet above normal high water level. Because of its strength and height the stone break-

40 water offers a positive barrier to the rough waters of storms and prevents the plunging of the seas over the top of the breakwater and the consequent scouring away of the sand of the beach at the lee side of the breakwater

45 which might otherwise occur. Because of the fact that it extends out a considerable distance into the water, the breakwater, if it is sand tight, rapidly accumulates sand on the side toward which the normal ocean current

50 is flowing, with the result that the beach builds up rapidly on that side of the breakwater usually for a considerable distance down the shore from the breakwater. The beach groin is a low, preferably wood structure located

55 at frequent intervals along the beach extending out across the beach from the usual shore

bulkhead at substantially right angles to the shore line and extending as far out into the water as is feasible. The groins should be built low, the upper edge of the groin approximating in height and conformation the normal or desired contour of the beach. Due to the practical difficulties in building the groins below normal water level it has not ordinarily been feasible to extend them more 60 than a relatively short distance beyond the normal high water line. These low groins offer but little resistance to waves passing over them and thus but little scouring out of the sand adjacent the groins occurs. Furthermore, as the sand accumulates on that side of the groin from which the normal ocean current approaches, the water spills over the low groin structure and thus permits sand to spill over, filling up the low spots and building up the beach on the far side of the groin. If the groins are constructed too high this spilling over of sand is restricted and the beach on the far side of the groin is washed 65 out and damaged. 70

Both the stone breakwater and the low 75 groin structure are valuable in safeguarding the beaches, but these structures are open to a number of serious objections and limitations. The beach groins are usually satis-

80 factory for protecting a beach which is in good condition. If the groins are installed before serious erosion of the beach has set in they will usually afford ample and inexpensive protection. However, it requires some- 85

thing in addition to simple groins to save a damaged beach and expedite its rebuilding. To protect and build up the beach the stone 90 breakwater is resorted to. Experience has shown, however, that while such a breakwater 95

affords very excellent protection for the beach at that side from which the normal ocean current approaches and builds up the beach rapidly on that side, it does, however, have a definite tendency to injure and even destroy 100 the beach at the other side of the breakwater. This destruction of the beach at the far side of the breakwater is in many places a very serious condition. The breakwater on the

one side impounds the sand proceeding along 105 the coast with the current but depletes the beach on the far side and the current, scouring along the far side of the breakwater, continually erodes the beach at that side for a considerable distance up the shore line. Certain 110 means have been proposed for restricting the destructive action which occurs at

the far side of the breakwater, as, for example, breakwaters or jetties provided with sand impounding basins near their inshore ends, retaining walls of various forms approximately paralleling the shore line and located below high water level, and the like. But, as far as I am aware, no reasonably simple structure which is practicable to build and which is operative to satisfactorily eliminate the difficulties above noted has been proposed.

It is a principal object of the present invention to provide a structure, particularly for use along shores where a definite current exists, which serves as a breakwater to furnish a barrier against storms and heavy seas, which saves the present beach from the destructive erosion of the ocean currents throughout a reasonable distance from the breakwater and which collects practically all of the sand flowing up the shore line with the current and distributes this sand on the beach at both sides of the breakwater, thus not only avoiding destruction of the beach on the far side of the breakwater as is inevitable with the present breakwaters, but effecting an actual constructive building-up of the beach at both sides of the breakwater. The main portion of the structure is essentially a breakwater extending out a considerable distance into the water. At its inshore end the breakwater does not extend up beyond the shore line according to the usual practice but rather terminates at or about the normal low water mark. Extending from this point in toward shore is a low groin portion having its outer and lower end substantially at low water mark. The groin portion extends back up the beach following the normal slope of the beach and is built so that its upper edge is reasonably near the present beach surface. The outer long seaward or main portion of the breakwater-pier, in addition to furnishing a barrier against high seas, serves also to intercept the sand drifting up the coast with the current. But instead of impounding the sand at the near side of the high breakwater portion, thus building up the beach at that side with the destruction of the beach at the other side, the structure at the low groin portion permits water and surplus sand to spill over to the opposite side of the breakwater and to continue up the beach with the normal current, thus filling in low spots and building up the beach on that side as well as on the near side of the breakwater. This intercepting and deflecting of the drifting sand shoreward and the correspondingly increased amount of sand which is passed directly on to the beach at the far side of the breakwater because of the spilling over at the low groin portion of the structure actually builds up the beach on the far side of the breakwater-pier more positively than would be the case before the breakwater was constructed when the

sand was moving undirected along the coast.

In its broad aspect the invention contemplates a structure extending out into the water and so constituted that it will intercept sand and deflect a substantial amount of sand inshore for beach building purposes. The structure has at one or more points along its length a portion which does not constitute a complete barrier to the sand carried along in the water currents. The idea is to intercept the sand proceeding along the coast and then to utilize the force of the normal currents to pass a certain amount of the sand over to the far side of the structure for use in building up the beach at that side. The point or points along the length of the structure at which this spilling over of sand is permitted will depend to a certain extent upon the condition of the beach and the places to which it is desired to direct the sand.

It is a further object of this invention to provide a breakwater structure of the class described which possesses all of the advantages and none of the disadvantages or limitations of the ordinary type of breakwater and beach groin at a cost which is materially less than the cost of the ordinary breakwater. It is also an object to provide a structure of this nature constructed in such a way that when finished it constitutes at no extra cost an adequate foundation for a spacious ocean pier.

A preferred embodiment of the invention is illustrated in the accompanying drawings in which Figure 1 is a plan view partly in section of the breakwater-pier, Figure 2 is an elevational view of the structure shown in Figure 1 and Figure 3 is a vertical sectional view taken on line 3—3 of Figure 1.

Referring to the drawings, the structure consists in general of two principal portions, an outer or seaward portion 1 and an inshore portion 2. The outer portion 1 is a heavy breakwater type of structure built principally of heavy rocks resting on the solid bed clay stratum 3 which is found below the sand level 4. This portion 1 of the structure extends to a certain height, preferably at or above the mean high water level indicated at 5. It is not considered necessary to build the portion 1 of the structure as high as the usual type of stone breakwater has heretofore been built. A height at or slightly above high water level after the rock has settled into its ultimate position of repose is sufficient. Thus the portion 1 serves as a breakwater for saving the beach and the water near the shore from the action of heavy seas. The inner portion 2 is a low gently sloping groin portion whose upper edge follows the desired beach contour and which throughout is not far above the normal beach level 6. As a specific illustration of the construction of the breakwater-pier, the inner end 7 of the groin portion 2 may conveniently be about eight feet 130

above low water level 8 and the lower end 9 at substantially the low water level 8. With this arrangement the portion 2 may conveniently be about 200 feet long. The seaward 5 or breakwater portion 1 may extend out into the ocean any desired distance as, for instance, three hundred feet. The portion 2 as here shown extends at substantially right angles to the shore line while the portion 1 extends 10 at somewhat of an angle to the portion 2. The idea is to extend the portion 1 in a direction such that it will be most effective as a breakwater and will also be effective in intercepting the sand drifting up the shore with 15 the ocean current. In the completed structure a low portion or gap is provided in the vicinity of the outer end 9 of the low groin portion 2. This gap is at its lowest point substantially at low water level. At high 20 water the outer part 9 of the low portion 2 is submerged, and normally a free passage of water along the shore over the lower end of the portion 2 is permitted.

For the breakwater portion 1 of the structure heavy rock is required. In order to handle such rock a large derrick must be used, and this in turn necessitates the provision of a strongly built trestle from which the derrick may be operated. Such a trestle is 25 ordinarily supported upon piling driven firmly into the hard sub-layer of clay underlying the sand. When the construction work is completed there is not much salvage value in the trestle because of the difficulty of with- 30 drawing the piling from the hard clay and the cost of retransporting it to another job. Accordingly, the structural features of the present breakwater-pier are based upon the idea of erecting in the first instance a permanent 35 trestle which will serve for constructional purposes and, when the construction work is completed, will constitute at no additional cost a suitable foundation for a large ocean pier. In the structure here shown, the foun- 40 dation of the trestle or pier consists of piling 10 driven down a considerable distance into the hard clay strata 11 and arranged with the tops of the piles at an appropriate uniform elevation. Widthwise of the struc- 45 ture suitable rows of piling are employed. Lengthwise the piling extends along the entire length of the structure, connecting at its inner end with the boardwalk structure 12 and terminating at its other end at the outer 50 end of the pier.

I have found that the breakwater portion 1 of the structure may be used effectively to intercept the sand drifting up the coast if it is provided with a sand-tight core. Experience has demonstrated that a sand-tight 55 breakwater will rapidly accumulate sand on that side from which the normal ocean current approaches. Accordingly, in the present structure a sand-tight core 13 is provided ex- 60 tending throughout the length of the break-

water portion 1 of the structure. The core 13 is preferably a wood unit consisting of planks driven at their lower ends into the clay strata 3, as indicated at 14, and supported at their upper ends by the piling 10 and by 70 suitable brace-work 15, in the manner indicated at 16. The sand-tight core 13 is built at the outermost row of piling 10 on that side of the pier opposite the side from which the normal ocean current proceeds. The core 13 75 is continuous with, and in effect is an extension of, the inshore portion 2. With the trestle-work and piling in place the construction of the core 13 is a relatively simple matter.

After the core 13 is in place the rock may 80 be laid. The piling of the pier offers a strong support for the core wall 13. Because of this substantial support given to the core wall by the piling of the trestle it is unnecessary on the inshore section, say the first two 85 hundred feet of the groin portion 1, to protect the wall by placing any rock along its near side, that is, the side from which the normal ocean current approaches. This greatly reduces the cost of the structure for 90 the reason that the cost of the rock is the highest item in the construction. Rapid accumulation of sand on the inner side of the core wall is assured, and thus a natural support for the wall 13 is rapidly built up. The 95 core wall 13 must be adequately supported at its far side by a sufficient quantity of heavy rock. The section of the structure shown in Figure 3 illustrates the type of construction 100 which is employed. The rock on the far side of the core wall, when feasible, should be laid on the clay strata 3 and not on the sand bottom 4. Ordinarily a large amount of the work necessary in removing the sand so that the rock may be laid on the clay bottom can 105 be eliminated by building the core wall 13 only a short distance ahead of the laying of the rock, in which case the current in sweeping around the outer end of the wall scours the sand away from the far side of the wall 110 and thus provides a suitable location for the rocks. As shown in Figure 1, it may be desirable to lay a certain amount of stone on the inner side of the core wall at the deep water end of the pier. Only a relatively small 115 amount of stone need be used and, as shown in Figure 3, the stone may be deposited directly on the sand 4 for the reason that the tendency at this side of the pier will be for the sand to build up further rather than to 120 wash out.

The breakwater-pier extends out into the water a considerable distance at somewhat of an angle so as to deflect the normal current in toward the shore. The length of the structure should be such as to intercept practically all of the sand proceeding up the coast because, as is well known, the sand drift is close in shore. The current with its entrained sand 125 will be deflected in toward shore, and the 130

travel of the water will, to a certain extent, be slowed up so that a large amount of sand will be directed inshore and deposited on the beach at the near side of the structure. It will thus serve in much the same fashion as do present properly constructed breakwaters in building up the beach on the side of the breakwater toward which the normal ocean current approaches. A great amount of this sand which is intercepted and deflected in toward shore will, however, spill over the low end of the groin portion 2 and thus pass on to the beach at the far side of the breakwater-pier. By intercepting all of the drifting sand and by spilling over a large proportion of it to the far side of the breakwater-pier in shallow water, a greater amount of sand is deposited on the beach at the far side of the structure than would be the case if no breakwater structure at all were present and the sand were drifting up the coast in its ordinary unobstructed course of flow. Thus not only does the present structure build up the beach at the near side of the breakwater and avoid destruction of the beach on the other side but actually builds up the beach on the far side as well as on the near side of the structure.

On badly damaged beaches it may be desirable to build either or both the breakwater portion 1 or the inshore portion 2 initially lower than the ultimate contour of the beach which is desired. After the structure has been in action for some time and the beach building has progressed to a sufficient extent, the top edges of the groin portion 2 and the breakwater portion 1 may be raised. The construction of the present invention easily permits of this due to the fact that both the core wall 13 and the groin portion 2 are wood structures receiving their support from the piling 10. Additional height may be attained by merely placing suitable wood members upon the tops of the old core wall and groin portion and securing such members to the piling 10. If, on a badly damaged beach, the breakwater-pier structure is made too high a temporary building-up of the beach at the near side will take place with a destruction of the beach at the far side, after the manner of the ordinary breakwater. This is avoided by initially building the parts lower than ultimately desired and later raising them after the beach development is under way.

After the construction work is finished the tops of the piling 10 may be suitably leveled off and an appropriate floor surfacing 17 laid upon the piling. The structure is then a finished pier obtained without any extra cost other than the cost of the actual floor surfacing for the pier.

The present invention, therefore, provides a breakwater-pier which serves a number of functions. It first constitutes a breakwater

to save the shore and waters near shore from the action of storms and heavy seas. It further serves to intercept all sand drifting up the coast with the normal ocean current and to direct this sand onto the beach for beach building purposes. It serves to build up the beach on that side from which the normal ocean current approaches. It prevents destruction of the beach at the other side of the structure. Not only does it prevent destruction of this beach, but actually builds up the beach. The structure employs only about one third the amount of rock commonly used in the ordinary type of breakwater, and its cost is therefore much less. After the construction work is finished, a pier floor may be placed upon the trestle foundation, and thus a long wide pier is provided at practically no additional cost.

I claim:

1. A beach protecting and beach building structure of the class described which comprises a substantially sand tight portion extending out away from the beach into the region of water driven sand rising to a height sufficient to intercept the major portion of such sand and extending at its inshore end at a lesser height below the normal high water line to a point seaward of the said high water line, whereby a passage of water and sand along the beach past the inshore end of the said sand tight portion is permitted.

2. A beach protecting and beach building structure of the class described for use on beaches along which a current normally flows in a definite general direction, which comprises a portion extending out into the water such distance and at such height as to intercept the major part of the sand drifting along the shore under the influence of said current, extending outwardly at an angle of less than 90° with the direction of approach of said current to thereby deflect said current and its entrained sand inshore, and terminating at its inshore end seaward of the normal high water line, whereby a part of the current and entrained sand deflected inshore will pass the inshore end of the structure onto the beach at the far side thereof and an inshore portion shoreward of said first mentioned portion rising to a height lower than normal high water level at a point seaward of the normal high water line, whereby a part of the said sand deflected inshore onto the beach is deposited upon the beach at the near side of the said inshore portion to a level corresponding to the height of said portion while a part of the said sand is carried over said inshore portion and is deposited upon the beach at the far side thereof.

3. A structure of the class described which extends out into the water a sufficient distance to intercept and deflect shoreward substantial portion of the sand drifting in the water currents, which rises to a height suffi-

85

- cient to constitute an effective sand barrier and which is provided with at least one portion along its length located shoreward of its seaward extremity which does not constitute 5 a substantially complete sand barrier, the major portion of said structure constituting a substantially complete sand barrier.
4. A beach protecting and beach building structure of the class described which comprises an outer portion extending out into the water a sufficient distance for intercepting and deflecting inshore sand proceeding along the coast, rising to a height below which the major portion of the water driven sand is carried and terminating at its inshore end on the seaward side of the normal high water line, an inner portion extending inshore from the inner end of said outer portion having its upper edge approximating the desired contour 10 of the beach and having its end which is adjacent the inshore end of said outer portion lower than said outer portion and below the normal high water level, whereby a part of the sand intercepted and deflected inshore by 15 said outer portion is directed upon the beach at the near side of the structure and is retained at said side by the said inner portion of the structure while a portion of said sand is carried past the inshore end of the said 20 outer portion and is thereby directed upon the beach at the far side of said structure.
5. A beach protecting and beach building structure of the class described for use on beaches along which a current normally flows 25 in a definite general direction, which comprises an outer breakwater portion extending out into the water a sufficient distance at a sufficient height to intercept the major part of the sand drifting along the shore under the influence of said current, extending outwardly at an acute angle to the direction of flow of said current to thereby deflect inshore said current and the sand carried thereby, and terminating at its inshore end on the 30 seaward side of the normal high water line, and an inner portion extending inshore from the inshore end of said breakwater portion at substantially right angles to the shore line having its upper edge approximating in slope 35 and in height the desired beach surface and having its outer end at substantially low water level, whereby sand deflected inshore by said outer breakwater portion is directed onto the beach at the near side of the structure and is built up to the height of said inner portion and additional sand is spilled over the top of said inner portion and serves to build up the beach at the far side of the structure.
6. A beach protecting and beach building 40 structure of the class described for use on beaches along which a current normally flows in a definite general direction, comprising a substantially sand-tight inshore section which at least one place therein is at an 45 elevation lower than high water level so that it does not constitute a complete sand barrier, and an outshore section which continues at an elevation above high water level to thereby 50 constitute a substantially complete sand barrier, the outshore section extending inshore at an angle of more than ninety degrees to the normal direction of flow of said current to thereby intercept and deflect the drifting sand shoreward to said inshore section and 55 said inshore section serving to retain behind it a portion of said sand and permit the surplus sand to spill over to the far side thereof.
7. A beach protecting and beach building 60 structure of the class described for use on beaches along which a current normally flows in a definite general direction, comprising an inshore section having its outer end at substantially the low water elevation, and an outshore section associated therewith which 65 continues out into the water at an elevation above high water level to thereby constitute a substantially complete barrier to water driven sand.
8. A beach protecting and beach building 70 structure of the class described for use on beaches along which a current normally flows in a definite general direction, comprising an inshore section having its outer end at substantially low water elevation, and an outshore section which continues out into the water at substantially high water elevation.
9. A beach protecting and beach building 75 structure of the class described which comprises a portion built principally of heavy 80 rock extending out into the water a sufficient distance at a sufficient height to intercept and deflect inshore sand proceeding along the coast and descending at its inner end on the seaward side of the normal high water line 85 to a lower level substantially below high water level, whereby water carrying the sand intercepted by said portion is permitted to proceed along the beach past the inshore end of the said portion onto the beach at the far 90 side of the structure, and a sand tight core associated with said rock portion for preventing passage of sand through the structure, whereby substantially all of the sand proceeding along the coast is made available for 95 beach building purposes.

PAUL T. ZIZINIA.
